FLANGE CLAMP SUPPORT

Goodloe E. Moore, Danville, Ill.

Application December 15, 1945, Serial No. 635,143

6 Claims. (Cl. 248—228)

1

This invention relates to a support connector attachment for attachment to a metal frame member.

In building construction and the like metal framework is usually incorporated whether said structure includes concrete, tile or other materials for ceilings, walls and floors. In the progress of construction certain lines, pipes, conduits etc. have to be carried along to supply at the point or elevation of work power etc. and water.

Temporary supports are usually cord or rope ties which chafe and fray as well as slip. For permanent support of so-called permanent lines which obviously in a concrete, steel reinforced building must be set before the concrete is applied the prior practice has included drilling and tapping some part of the framework and then threading into such hole a bolt that carries a line support. Usually two bolts per anchorage are required. Obviously this weakens the framework. It also is expensive because of the application time required. If such a support is for temporarily use only, the framework obviously is correspondingly weakened when the support is removed and also the cost of removal is expensive.

The chief object of the present invention is to provide a support connector for metal framework application which can be readily and inexpensively applied thereto and expeditiously applied thereto for permanent and temporary use without any weakening of the framework, and if for temporary use can be quickly and inexpensively detached from the framework leaving the latter in its initial condition.

The chief feature of the present invention resides in providing a framework flange embracing anchor plate in channel or U-shape section form which in turn centrally supports an offset or projecting support portion of cantilever type.

Other objects and features of the invention will be set forth hereinafter.

The full nature of the invention will be understood from the accompanying drawings and the following description and claims:

In the drawings Fig. 1 is a central sectional view of a metal truss structure, adjacent conduit and the support connector applied thereto, the truss being one suitable for roofs, bridges or the like.

Fig. 2 is a perspective view of the support connector.

Fig. 3 is a view similar to Fig. 1 and of a modified form of the support connector, a conduit, and frame member, the frame member being of flange type, such as an I or H beam or even an angle.

Fig. 4 is a side view of the support connector and a portion of the conduit shown in Fig. 3.

In Figs. 1 and 2 of the drawing 10 indicates generally a portion of a truss structure having a

2

lateral flange 11 with one face 12, an opposite face 13 and the side edge 14. Such base portion may even constitute an angle or an H or I beam providing a projecting flange such as illustrated in Fig. 3 to which reference will be had hereinafter.

In Figs. 1 and 2 the anchorage or base portion of the connector comprises a plate bent to U-shape section formation having the upper portion 15, the root portion 16 and the lower portion 17. The terms upper and lower obviously are relative terms and are not to be taken literally.

As illustrated portion 17 is of major length and portion 15 is of minor length. The plate 15 preferably is of foraminated type having a comparatively large number of openings 18 therethrough. Interposed between the flange and U-sectioned plate is adhesive material 19 which, when applied to the flange where the connector 20 is to be secured, and the plate is applied thereto squeezes outwardly as at 20 to form locking lugs in the plate as well as wicks to facilitate cement solvent evaporation thereby materially expediting the setting up of the cement for rigid retention of the plate upon the flange.

The cement preferably used may be that now commercially sold under the name "Miracle."

This "Miracle cement," or an equivalent one, is of the following character:

30 Synthetic resins and solvents compounded as required to produce the aforesaid or an equivalent adhesive. Such an adhesive preferably contains no asphalt and a sulphur content of less than three-fourths of one per cent. Such an adhesive 35 develops shear and tensile strength so that the same is equally applicable for securing hangers to sidewalls and ceilings.

This adhesive when dry bonds tenaciously to almost all types of surfaces, especially those initially mentioned herein and is strong, tough and flexible in character.

Such an adhesive affords a permanent bond as well as a strong initial bond, for example, six pounds per square inch adhesion within an hour and seventy-five pounds per square inch adhesion after the adhesive has set thoroughly. Consequently, each hanger of four square inches is secured to the surface with an adhesive force of twenty-four pounds at the end of one hour and three hundred pounds when fully set.

Such an adhesive, furthermore, is flexible and never becomes brittle so far as now known. It is of waterproof character both in salt and fresh water, so that should spray, etc., contact the support or moisture condense thereon, the adhesive on such support remains comparatively unaffected. So far as now known, such adhesive also remains unaffected comparatively speaking, by temperature changes, same having been tested from as low as sixty degrees below zero to two hundred

fifty degrees above the same, both being Fahr-enheit.

Rigid with the plate, which initially may be square in outline, and centrally thereof, there is secured by welding or the like portion or stem 21. Stem 21 projects outwardly and oppositely from portion 17 and terminates in an arcuate support portion 23, the connection 22 therebetween thus being of cantilever type. Herein the arcuity is greater than 180°, in fact is greater than 300° but it may be less or greater as desired or required.

The free end, see Fig. 2, may be longitudinally slotted as at 24 if desired. In this form of the invention the curved portion 25 constitutes a yielding but somewhat resilient connection for the cantilever portion 22 and thus the end embraced or supported conduit 26 readily can be positioned closer to the flange edge 14 or more distant therefrom as desired or required and obviously can be readily raised or lowered to lie above the plane or below the plane including the flange, if it is desired not to have the conduit lie coplanar therewith as illustrated in Fig. 1. The free end obviously may take any form as desired or required, and the conduit can be clamped therein by screws or other devices or by the free tongues as illustrated or merely may be partially encompassed by that end without clamping.

Reference will now be had to Figs. 3 and 4. In Fig. 3 30 indicates a flange of an I or H beam having upper face 31, lower face 32 and side edge 33. The U-shaped foraminated plate includes upper portion 34, root portion 35 and lower portion 36. It is provided with holes 37. The cement between the flange and plate is indicated by numeral 38 and the locking lugs by numeral 39.

Suitably secured as by welding or the like and centrally of the plate is collar 40. It is centrally tapped at 40^a to take screw or bolt 41 by which arm 42 is anchored to the plate and collar. This arm may be of any desired length and provided with a longitudinally directed notch or slot to pass the bolt 41 by which the cantilever type arm is connected to and supported by the collar and plate.

When the bolt 41 is loosened, the arm 42 can be slid relative to the bolt which will position the arcuate sectioned end 43 closer to the flange edge or more distant therefrom whereby the conduit 44 resting on end 43 may be positioned as desired or required. When such adjustment is not required the slot is merely a hole 45 to pass the bolt 41 as shown.

The arm 42 may not be as short as illustrated but may be longer and have an inclined portion to position the free end 43 and conduit 44 at an elevation greater than that illustrated.

Preferably the plate at its central portion is free of perforations and the threaded hole 40^a is coextensive with the collar. Thus if in this form of the invention the plate and collar only initially be applied to the flange subsequent application of the cantilever arm and anchoring screw will not rupture the cement connection between the plate and flange.

As in the first form the free end 43 may be longitudinally slotted at 46, and a conduit clamping screw or the like associated therewith, if desired. This is illustrated in Fig. 1. It is preferred on Fig. 3 to illustrate the conduit support only form of the basic invention.

The form of the invention illustrated in Figs.

3 and 4 is applied and utilized as previously described relative to the form illustrated in Figs. 1 and 2 insofar as they are commonly disclosed.

While the invention has been illustrated and described in great detail in the drawings and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. A support and connector structure adapted for cementitious connection to a projecting flange and comprising a U-shaped sectioned portion for flange edge embracement, the cementitious connection between that portion and the flange being substantially coextensive with the entire inner surface of the U-shaped portion and positioned between the portion and the flange for the triple surface adhesion thereto, a cantilever type support projecting oppositely from the flange and carried by the U-shaped portion, the support at its free end having a suitable conformation for support purposes, and means at the other end of the cantilever support rigidly securing the same to the U-shaped sectioned portion in outboard relation to the flange.

2. Structure as defined by claim 1 wherein the supported end of the cantilever portion is spaced from the U-shaped portion but rigidly connected thereto, and the free end of the cantilever portion being otherwise independent of the U-shaped sectioned portion.

3. Structure as defined by claim 1 wherein the supported end of the cantilever portion is spaced from the U-shaped portion but rigidly connected thereto by a bend portion.

4. Structure as defined by claim 1 wherein the supported end of the cantilever portion is spaced from the U-shaped portion but rigidly connected thereto by a tapped collar, and means threaded into the collar and securing the supported end of the cantilever portion to the collar, and the free end of the cantilever portion being otherwise independent of the U-shaped sectioned portion.

5. Structure as defined by claim 4 wherein the supported end of the cantilever portion is slotted longitudinally and the last-mentioned means extends through the slot.

6. Structure as defined by claim 5 wherein the free end of the cantilever portion is slotted longitudinally for the purpose described.
